(57) **CLAIM**

The ornamental design for an auger adapter and connector assembly, as shown and described.

DESCRIPTION

FIG. 1 is an isometric view of an auger adapter and connector assembly embodying the new design, having a short-shafted and short-bladed auger;

FIG. 2 is an isometric view of the embodiment of FIG. 1, but showing the auger adapter and connector assembly in a disassembled state;

FIG. 3 is a right side elevation view of the embodiment of FIG. 1;

FIG. 4 a left side elevation view of the embodiment of FIG. 1;

FIG. 5 is a bottom plan view of the embodiment of FIG. 1; FIG. 6 is a top plan view of the embodiment of FIG. 1; FIG. 7 is a rear elevation view of the embodiment of FIG. 1;

FIG. 8 is an enlarged isometric view of the disassembled components of the connector assembly portion of the design of FIG. 1;

FIG. 9 is an enlarged elevation view of the disassembled components of the connector assembly portion of the design of FIG. 1;

FIG. 10 is an enlarged elevation view of the assembled connector assembly portion of the design of FIG. 1;

FIG. 11 is another enlarged isometric view of the disassembled components of the connector assembly portion of the design of FIG. 1;

FIG. 12 is another enlarged elevation view of the assembled connector assembly portion of the design of FIG. 1;

FIG. 13 is an enlarged right side elevation view of the short-shafted and short-bladed auger portion of FIG. 1;

FIG. 14 is an enlarged isometric view of the short-shafted and short-bladed auger portion of FIG. 1;

FIG. 15 is an isometric view of a second embodiment of the assembled auger adapter and connector assembly, having a medium-shafted and short-bladed auger;

FIG. 16 is an isometric view of the embodiment of FIG. 15, but showing the auger adapter and connector assembly in a disassembled state;

FIG. 17 is a right side elevation view of the embodiment of FIG. 15;

FIG. 18 is a left side elevation view of the embodiment of FIG. 15;

FIG. 19 is a bottom plan view of the embodiment of FIG. 15; FIG. 20 is a top plan view of the embodiment of FIG. 15;

FIG. 21 is a rear elevation view of the embodiment of FIG. 15;

FIG. 22 is an enlarged right side elevation view of the medium-shafted and short-bladed auger portion of FIG. 15; FIG. 23 is an enlarged isometric view of the medium-shafted and short-bladed auger portion of FIG. 15;

FIG. 24 is an isometric view of a third embodiment of the assembled auger adapter and connector assembly, having a long-shafted and long-bladed auger;

(Continued)

FIG. 25 is an exploded isometric view of the embodiment of FIG. 24;
FIG. 26 is a right side elevation view of the embodiment of FIG. 24;
FIG. 27 is a left side elevation view of the embodiment of FIG. 24;
FIG. 28 is a top plan of the embodiment of FIG. 24;
FIG. 29 is a bottom plan view of the embodiment of FIG. 24;
FIG. 30 is a rear elevation view of the embodiment of FIG. 24;
FIG. 31 is a right side elevation view of the long-shafted and long-bladed auger portion of FIG. 24; and,
FIG. 32 is an isometric view of the long-shafted and long-bladed auger portion of FIG. 24.
The broken lines depict portions of the auger adapter and connector assembly, in which the design is embodied that form no part of the claimed design.
